UNITED STATES PATENT OFFICE

134,483

DESIGN FOR A PROJECTION APPARATUS

Albin A. Gradisar, Buffalo, William F. Peck,
Snyder, and John T. Armbruster, Niagara Falls,
N. Y., assignors to Spencer Lens Company,
Buffalo, N. Y., a corporation of New York

Application April 17, 1942, Serial No. 106,596

Term of patent 14 years

To all whom it may concern:

Be it known that (1) Albin A. Gradisar, (2) William F. Peck, and (3) John T. Armbruster, citizens of the United States, residing at (1) 67 Ruspin Avenue, Buffalo, N. Y., (2) 245 Bernhardt Drive, Snyder, N. Y., (3) 217 74th St., Niagara Falls, N. Y., in the counties of (1) Erie, (2) Erie, and (3) Niagara, and State of New York, have invented a new, original, and ornamental Design for a Projection Apparatus, of which the following is a specification, reference being made to the accompanying drawings, forming a part thereof.

Fig. 1 is a front perspective view of a projection apparatus embodying our design.

Fig. 2 is a side view thereof.

Fig. 3 is a top plan view thereof; and

Fig. 4 is a front view thereof.

We claim:

The ornamental design for a projection apparatus, substantially as shown.

ALBIN A. GRADISAR.
WILLIAM F. PECK.
JOHN T. ARMBRUSTER.
